UNITED STATES PATENT OFFICE.

EDWARD C. KAHN, OF MILWAUKEE, WISCONSIN.

LIQUID-FUEL BURNER.

1,269,190.

Specification of Letters Patent. Patented June 11, 1918.

Application filed May 28, 1917. Serial No. 171,338.

To all whom it may concern:

Be it known that I, EDWARD C. KAHN, a citizen of the United States, and resident of Milwaukee, in the county of Milwaukee and State of Wisconsin, have invented certain new and useful Improvements in Liquid-Fuel Burners; and I do hereby declare that the following is a full, clear, and exact description thereof.

10 My invention relates to certain new and useful improvements in liquid fuel burners and is a simplification of that type of burner exemplified in an application filed by me February 5, 1917, Serial No. 146,586, allowed April 28, 1917.

It is in general the object of my invention to simplify the structure and to increase the efficiency of burners of this character by providing a mixing and expansion chamber 20 wherein air in correct proportion is drawn in by the entrance of fuel vapors and thoroughly co-mingled with the vapors by reason of the air and gas being caused to travel in eddying currents prior to their entrance 25 into the burner head; and in which the fuel vapors fully expand in their whirling course through the chamber.

Another object resides in the provision of a burner head juxtaposed and in communication with the mixing and expansion chamber, and concaved in its under side to permit the continuation of the whirling movements given the gases in the mixing chamber, and provided with a series of spaced 35 radial slots in its outer peripheral edge to allow escapage of the gases for ignition.

A further object is to provide a burner head having its jet apertures so arranged with respect to the supply passages thereof 40 as to prevent the possible occurrence of combustion within the burner head, it being more specifically an object to effect this result by so constructing the expansion and mixing chamber as to insure the proper flow 45 of fuel gas through the jet apertures.

With the above and other objects in view which will appear as the description proceeds, my invention resides in the novel construction, combination and arrangement 50 of parts substantially as hereinafter described and particularly defined by the appended claims, it being understood that any changes in the precise embodiment of the herein disclosed invention may be made as 55 come within the scope of the claims.

In the accompanying drawings I have

illustrated one complete example of the physical embodiment of my invention constructed according to the best mode I have so far devised for the practical application 60 of the principles of my invention, in which:

Figure 1 is a sectional view through my burner taken on the plane indicated by line 1-1 of Fig. 2, and

Fig. 2 is a top plan view thereof with 65 parts broken away to more clearly illustrate structural details.

Referring now more particularly to the accompanying drawing, 5 designates the up-standing supply pipe of the burner, and this supply pipe is in communication with a super-heating pipe 6 supported from the burner head by a bracket 7 and having its end 8 in threaded engagement and communicating with the intake 9 of the vapor spray nozzle 10. This spray nozzle comprises a needle valve 11 of conventional design adapted to engage a spray opening 12, the shaft of the valve being threaded for engagement with the internally threaded 75 shank 13 of the nozzle and adapted to be manipulated by a handle 14.

The spray opening 12 is in line with the opening of the mixing or expansion chamber which comprises a central channel or intake 85 15 divided by a pair of parallel walls 16 which terminate just beyond the outlet opening or aperture 17 in the top wall 18 of the mixing chamber, these walls 16 dividing the circular mixing or expansion chamber into 90 a series of three compartments; 15, 20 and 20', the central compartment 15 being of a depth greater than that of the two outer compartments 20 and 20'. The top wall 18 is provided at its outer peripheral edge 95 with an upwardly and outwardly inclined flange 21 which forms a recess in which is seated a burner cap 22 forming with the wall a burner head and having its peripheral edge slotted as at 23 to provide jet 100 apertures, said burner having its peripheral edge inclined to correspond with the incline of flange 21 and spaced therefrom a distance equal to the width of jet apertures 23; lugs 24 being provided to retain 105 this spaced relation between the burner cap and flange 21.

The outer periphery of the top wall 18 is provided with spaced ears or lugs 25 for spacing the same from a hood 26 to form 110 an annular air inlet passage, which has its upper portion 27 extending above the burner

cap inwardly and upwardly inclined; suitable fastening screws 28 being provided passing through the hood and engaging the lugs 25 to secure the same in position.

5. For initially heating the mixing or expansion chamber and spray nozzle, suitable troughs or inverted cup members 29 and 30 are provided, the trough 29 being secured to the spray nozzle by means of a stub bolt 31 and the trough 30 being secured around the fuel supply pipe 5, and as the manner of using the same will be readily understood by those skilled in the art to which an invention of this character appertains, further description is thought unnecessary.

As will be understood, my burner may be supported by the up-standing fuel supply pipe, or may be supported by a suitable pedestal 32 carried by the bottom wall of the mixing chamber, and that the operation of the burner is as follows: The cups 29 and 30 are first filled with the liquid fuel and then ignited to pre-heat the spray nozzle, the mixing or expansion chamber and super-heating pipe, and when the several parts have been thoroughly heated, the supply of fuel is then turned on and ignited. The vaporized fuel will spray from out the spray opening 12 into compartment 15 where the same will be thoroughly co-mingled with air drawn in by the fuel, some of it passing directly from the chamber 15 through the opening 17 and the best part of this vapor gas passing around into chambers or compartments 20 and 20' and then out opening 17 where the same will be distributed through the jets 23 where it is ignited, as will be obvious.

What is claimed is:—

40. 1. In an oil burner, a mixing chamber having an outlet opening, partitions in the mixing chamber defining a series of communicating compartments each in communication with said outlet opening, and an inlet communicating with one of said compartments.

50. 2. In an oil burner, a mixing chamber having a central aperture in its top wall, and a central compartment in the mixing chamber defined by a pair of partitions therein communicating with the atmosphere to provide an intake opening, the said partitions extending into said chamber to a point spaced from the rear portion of the side peripheral wall of the chamber.

55. 3. In an oil burner, a mixing chamber provided with a centrally apertured top wall and an intake opening for the chamber and defined by a pair of partitions in the chamber extending to a point just beyond said central aperture.

60. 4. In an oil burner, a mixing chamber provided with an aperture in its top wall and an intake opening for the chamber and defined by a pair of partitions in the chamber

extending to a point just beyond said central aperture, the compartment between the partitions being of greater depth than the outer compartments.

5. In an oil burner, a mixing chamber and burner head comprising a circular dished plate having a central aperture therein, a distributing burner cap seated in the dished plate and provided with a series of radial slots forming jet openings, means spacing the peripheral edge of said burner cap from the inner peripheral wall of said dished plate, a circular mixing chamber formed on the under side of said plate and in communication with said central aperture, and an inlet opening for the mixing chamber.

6. In an oil burner, a mixing chamber and burner head comprising a circular dished plate having a central aperture therein, a distributing burner cap seated in the dished plate, a circular mixing and expansion chamber formed on the under side of said plate and in communication with the central aperture, said mixing and expansion chamber being eccentric with said plate, and an inlet for the mixing chamber.

7. In an oil burner, a mixing chamber and burner head comprising a circular dished plate having a central aperture therein, a distributing burner cap seated in the dished plate, a circular mixing and expansion chamber formed on the under side of said plate and in communication with the central aperture, said mixing chamber being eccentric with said plate, and an inlet opening for the mixing chamber said inlet being formed by a pair of parallel partitions extending beyond the periphery of said chamber.

8. In an oil burner, a fuel supply having means for vaporizing the fuel, a spray nozzle at the termination of the fuel supply, a central channel formed by a pair of parallel walls, an expansion chamber communicating with said channel, said parallel walls extending into the chamber and defining a pair of outer communicating compartments and said central channel forming a central compartment, an outlet in the top wall of the expansion chamber and communicating with the three compartments, and a burner head disposed above the outlet, the fuel vapor passing into the central channel and collecting sufficient air and expanding in said channel, part of the vapor passing out of the channel by way of said outlet, and the major part of the vapor passing around the parallel walls into the outer compartments where it is further expanded and then passes through the outlet to the burner head substantially as described.

9. An oil burner comprising a centrally apertured burner head and a mixing chamber comprising a series of communicating compartments each in communication with

the burner head aperture, the mixing chamber being provided with baffle walls adapted to cause the gas to travel in eddying currents prior to its entrance into the afore-
5 said burner head.

10. An oil burner of the class described, comprising a circular dished plate provided with a central aperture, a distributing burner cap seated in the dished plate and evenly spaced from the peripheral wall thereof, a mixing and expansion chamber formed on the under side of said plate, a pair of partitions extending from the inner portion of said chamber to a point outward of the peripheral wall thereof, said partitions defining
15 a series of communicating compartments

each communicating with said central aperture, the central compartment defined by said partitions providing an inlet opening, a spray nozzle in line with the open mouth 20 of said central compartment, a super-heating pipe connected with the spray nozzle and having a portion thereof disposed over the distributing burner cap, and a source of supply connected with said super-heating 25 pipe.

In testimony that I claim the foregoing I have hereunto set my hand at Milwaukee, in the county of Milwaukee and State of Wisconsin.

EDWARD C. KAHN.
